(57) **CLAIM**

We claim the ornamental design for an ear piece, substantially as shown and described.

DESCRIPTION

FIG. 1 is a perspective view of an ear piece in accordance with the present design. The ear piece can, for example, be a wireless ear piece for use with a cellular phone (e.g., Bluetooth).

FIG. 2 is a front view for the ear piece.

FIG. 3 is a rear view for the ear piece.

FIG. 4 is a top view for the ear piece.

FIG. 5 is a bottom view for the ear piece.

FIG. 6 is a right side view of the for the ear piece; and,

FIG. 7 is a left side view for the ear piece.

The features shown in broken lines in the various Figures are for illustrating environmental structure and form no part of the claimed design.

1 Claim, 2 Drawing Sheets
